Estate of Martin R. Kenyon

UNITED STATES PATENT OFFICE.

ANNA E. KENYON, (ADMINISTRATRIX OF MARTIN R. KENYON, DECEASED,) OF PROVIDENCE, RHODE ISLAND, ASSIGNOR TO UNION EYELET COMPANY, OF SAME PLACE.

BUTTON-FASTENER.

SPECIFICATION forming part of Letters Patent No. 244,998, dated August 2, 1881.

Application filed September 15, 1880. (No model.)

To all whom it may concern:

Be it known that MARTIN R. KENYON, deceased, did invent an Improvement in Button-Fasteners, of which I, ANNA E. KENYON, of Providence, in the county of Providence and State of Rhode Island, administratrix of the estate of said MARTIN R. KENYON, deceased, declare the following to be a full, clear, and exact description, reference being had to the accompanying drawings, forming a part of this specification in explaining its nature, in which—

Figure 1 is a plan of the blank used in making the fastening. Fig. 2 is a side elevation of the fastening. Fig. 3 is a section illustrating the use of the fastening. Fig. 4 is a plan of a blank having a solid seat.

This invention has for its object the following-described button-fastener; and it is an improvement on the one described in Patent No. 193,611, granted to said MARTIN R. KENYON, dated July 31, 1877.

It consists in the metallic base or seat *a*, which may or may not have its center removed, and the tongue *b*, which is a continuation of one end of the seat or base, and which is curved over the seat or base, as shown, is provided with the loop *c*, and the portion *f*, which projects beyond the other end of the seat, and is adapted to be turned over upon the under side of the seat and clinched or hooked thereon.

To apply the fastener to the eye of the button, the eye is inserted through a hole cut in the material to which the button is to be secured. The tongue of the fastener is passed through the eye until the loop engages therewith, and the end of the tongue turned over and hooked upon or otherwise secured to the end of the seat or base.

By this construction a loop for receiving the eye of the button long enough to pass through the material is provided, and this is of considerable advantage, as, in order to fit the base or seat of the fastening snugly to the material, it is desirable that the loop should pass through the material and lay hold of the eye of the button upon the outside of the material, rather than that the eye of the button should pass through the hole and the loop be entirely upon the inside of the material; and the fastening is held in position with the base or seat snugly against the side of the material much better when the loop passes through the material and takes the eye of the button upon the outside.

Having thus fully described the invention of MARTIN R. KENYON, deceased, what I claim as his invention, and desire to secure by Letters Patent of the United States, is—

As an improved article of manufacture, a button-fastening consisting of the flat base or seat *a*, and the tongue *b*, extending from one end thereof, curved backwardly parallel with the base or seat, and provided with the loop *c*, as represented, and with the portion *f* extending beyond the end of the seat, and adapted to be turned over upon the under surface of the end of the base or seat, and hooked or clinched thereon, substantially as and for the purposes described.

ANNA ELIZABETH KENYON,
Administratrix of the estate of Martin R. Kenyon, deceased.
